UNITED STATES PATENT OFFICE.

ALFONSO SORIENTE, OF BROOKLYN, NEW YORK.

DESIGN FOR A CANE.

Application filed April 1, 1927. Serial No. 21,434. Term of patent 7 years.

To all whom it may concern:

Be it known that I, ALFONSO SORIENTE, a citizen of Italy, residing in Brooklyn, in the county of Kings, in the State of New York, have invented a new and original and ornamental Design for a Cane, of which the following is a specification, reference being had to the accompanying drawing, forming a part thereof.

The figure is a front elevational view of the cane, showing my design.

I claim:

The ornamental design for a cane as shown.

ALFONSO SORIENTE.
